REVERSIBLE AIR CIRCULATING SYSTEM

Ludwig O. Solberg, Wenatchee, Wash.

Application July 7, 1942, Serial No. 449,983

1 Claim. (Cl. 98—54)

This invention relates to improvements in methods of and means for circulating air. More particularly, it has reference to systems designed for the circulation and cooling of air for use in the refrigerating of buildings, such, for example, as those used for the storage and preservation of apples and other kinds of perishable food products; it being the principal object of this invention to improve upon those systems of one-way, forced air circulation, now generally in use, wherein the cooling air is propelled or drawn through a cooling unit, thence delivered into ducts which convey it to and discharge it into the area to be cooled, thence to return through other ducts to the starting point for recirculation through the system.

To impart a better understanding to the objects and advantages of the improvements embodied by the present invention as applied to one of the typical uses of such systems, it will be here explained that apples may be kept for an extremely long time in good edible condition, without loss of firmness and flavor, if maintained in air of appropriate humidity and a temperature of approximately 31° F. However, to insure the safe keeping of the fruit, it is required that it be picked when at a certain exact condition of ripeness, that the field heat be immediately reduced and finally the core temperature of the apple be established at the above stated degree of temperature and that that temperature be maintained in the apple during its period in storage.

In present-day cold storage systems designed for the keeping of apples, the cooling medium is continuously circulated and it is generally the case that the cold air is delivered into the storage space along the center line of the room, and is caused to flow toward the opposite side walls, and is withdrawn from along the outside walls for return to the air cooling means for re-cooling preparatory to recirculation.

In the disposition of apples in the storage space, they are received approximately at field temperature. The boxes in which they are packed are stacked first along the outside walls of the storage area and the filling of the space progresses from the outside walls toward the center line of the area. Therefore, the cold air, as delivered into the area along the center line of the building must flow a distance equal to half the width of the area and consequently takes up heat from the intermediate air and objects before it reaches the fruit.

Furthermore, in the filling of the storage space, the workmen who bring the fruit into the area on hand trucks, are directly subjected to the chilling blast of cold air which creates a very bad health condition.

It is also an objectionable condition that, in a one-way system of circulation, the fruit nearest

the points of supply of cold air will be cooled to a lower degree of temperature and there can be no uniformity of condition throughout the area. Therefore, in order to reduce the temperature of the fruit that is farthest away to the desired degree, it is necessary to cool that which is close, to a degree below that which is considered best.

In view of the objections and conditions set out in the foregoing explanatory matter, further objects of the present invention are:

To provide means whereby the direction of circulation of the cooling air may be reversed at will as a means of expediting the extraction of field heat from the apple, and thereby making it possible to approach a uniformity of temperature in all parts of the storage area; to employ lower temperatures during the initial cooling off period without danger of freezing the fruit, and to improve the health conditions of the workmen in filling the storage area.

Furthermore, to provide a system of ducts for the cooling air in connection with dampers operable for the reversal of direction of air flow, whereby this reversal in the storage area is accomplished without change in the direction of air flow through the cooling unit, and thus making possible the washing of the air in each cycle of its travel.

Also, to provide a novel system of ducts for the distribution of cooling air, in combination with a circulating fan, an air cooling unit and an arrangement of dampers whereby the direction of air flow may be reversed, controlled and regulated without change in direction of the fan or direction of air through the cooling unit.

Still further objects of the invention reside in the various novel details of construction of the building, and in the arrangement of ducts and combination of parts and their mode of operation, as will hereinafter be fully described.

In accomplishing these and other objects of the invention, I have provided the improved details of construction, the preferred forms of which are illustrated in the accompanying drawings, 45 wherein—

Fig. 1 is a cross sectional view lengthwise of a building equipped with an air circulating and cooling system embodied by the present invention.

Fig. 2 is a cross section of the building, as seen on the line 2—2 in Fig. 1.

Fig. 3 is a perspective view illustrating the arrangement of ducts in the building, their connections and the various dampers therein for reversing and controlling the direction of circulation of air within the cooling areas.

Fig. 4 is a sectional detail showing the setting of the dampers for causing the flow of air to be reversed in direction from that indicated in 60 Fig. 1.

Fig. 5 is a detail of damper control means.

Referring more in detail to the drawings—

The building here illustrated is merely representative of one form of construction that is suitable for the storage and cooling of apples, and it is to be understood that the materials from which it is made, its general details of construction, its dimensions and number of stories or floors, might be varied to meet special conditions or specific requirements. As here shown, the building, designated in its entirety by numeral 1, has three floors, designated respectively by reference numerals 2, 3 and 4, and it provides three rooms or areas, designated by letters *a*, *b* and *c*, for the storage of the boxed or crated fruit. The first and second floors, 2 and 3, are of solid, that is, of air-tight construction, while the third floor 4, is formed of spaced planks, providing for flow of air through the floor for the cooling of both areas *b* and *c* by air delivered from the same supply ducts, as presently will be explained. The floor 3 serves as a ceiling for the area *a*, while the area *c* has an air-tight ceiling 5.

Erected at the top of the building, centrally thereof and extending in its longitudinal direction, is a penthouse 6 for the air propelling fan and cooling means. Preferably, the fan is motor driven and is of the "Sirocco type" here designated by reference numeral 10. It is mounted on a shaft 11 and is contained within openings 13 registering with the opposite ends of the fan. This housing 12 has an air discharge duct 14 leading therefrom directly into an air cooling unit designated at 15, including pipe coils 16 in suitable number and kind, to reduce the air to a desired degree of temperature, and at the outlet of the cooling unit, are free moisture eliminators 16'. Leading from the housing of the air cooling unit 15 is a downwardly and rearwardly directed air delivery duct 17, through which the cooled air is distributed to ducts, presently described, for delivery to the areas to be cooled.

The present duct system, which may be understood best by reference to Fig. 3, comprises an upper duct 20 for accommodating the two upper areas *b* and *c*, and a lower duct 21 for accommodating the lower area *a*. Each of these ducts 20 and 21 extends horizontally, lengthwise of the building, and medially of and through the full length of the area it is to accommodate. Also, each duct is located adjacent the ceiling, or top of the accommodated area. The duct 21, at that end of the building which, for convenience in reference, will be referred to as the back end, has a vertical leg 21a extending upwardly therefrom, and this communicates at its upper end with the lower end of the duct 17 through the rear end wall of the latter, as noted best in Fig. 1. Likewise, the duct 20 communicates with the duct 17 through its bottom wall and immediately adjacent the communicating connection with duct 21a.

Within the duct 17 there is a hingedly mounted damper deflector plate, or valve 23, that is manually adjustable to different positions for the purpose of proportionately dividing the volume of cold air as supplied through duct 17 for delivery to the two ducts 20 and 21 so as to proportionately accommodate the areas supplied.

The ducts 20 and 21 have openings 24 formed at intervals therealong in their bottom walls through which air may be discharged into or received from the areas which these ducts accommodate.

Also, communicating with the duct 17, and

opening thereinto through an opening in its bottom wall between the opening for communication with duct 21 and its connection with the cooling unit, is a duct 25 used in the reversing of direction of flow of circulated air. This duct extends horizontally and is directly below the cooling unit and fan, lengthwise of the building and directly above duct 20. It extends to the front end wall of the building, where it is divided into two branches that continue as oppositely directed, horizontal ducts 25r and 25L, respectively, to the opposite front corners of the building. At the near corner of the building, as viewed in Fig. 3, the duct 25r communicates with a horizontal duct 27 that extends along the side wall of area *c*, below ceiling 5, to the rear end wall of the building. Also, there is a duct 28 that extends directly downward from the outer end of duct 25r to below the first floor and then turns and continues horizontally along the ceiling to the rear corner of the area *a*. Likewise, the duct 25L communicates at its outer end with a horizontal duct 29 that extends horizontally along the side wall of the building, adjacent the ceiling of area *c* and to the rear wall, and there is a duct 30 that extends downwardly from the end of duct 25L to the lower area *a*, then turns rearwardly and extends along the ceiling of that area to the rear corner of the building.

The ducts 27 and 29, also the horizontal portions of ducts 28 and 30, are provided in their bottom walls at regular intervals with openings 32 for the inflow or outflow of air.

Contained within the outer end portions of duct 25r and leading up to the junction of ducts 27 and 28 therewith, is a division baffle 35 designed to proportionately divide the flow of air as delivered to the ducts 27 and 28. Likewise, located in the outer portion of duct 25L is a similar baffle designed for dividing the flow of air to ducts 29 and 30.

The penthouse 6 which encloses the fan 10, the cooling unit 15 and the duct 17 therein, is air-tight, and, in fact forms a longitudinal duct 40 enclosing these parts. At one end, the duct 40 communicates directly through an opening 42 in the top wall of duct 17, with the ducts 20 and 21. The opening 42 is fitted with a damper 43 that is adapted to be adjusted between open and closed positions to permit or prevent flow of air through the opening.

Located within the duct 17 to close it against longitudinal flow of air therein, is a damper 45. This is disposed between the opening into the duct 25 and opening into duct 20, and it may be adjusted between open and closed positions. Also, there is a damper 46 in the entrance opening from duct 17 into duct 25, and this damper likewise is adjustable between open and closed positions.

In the top wall of duct 25 is an opening 48 providing direct communication with one end of the duct 40, and this opening is fitted with a damper 49 adapted to be moved between closed and open positions, to prevent or to permit flow of air to the duct 40 from duct 25. Also, located in the duct 25 between the damper 49 and damper 46, is a damper 50, and this is adjustable between open and closed positions.

In the present drawings, the various dampers, as best shown in Fig. 4, have been illustrated as of the pivoted louvre type. It is to be understood, however, that various ways and means might be employed for the control of these dampers, and it is not the intent that the invention shall be

confined either to any special type of damper or any special way of controlling the dampers used, but rather that any suitable type of damper or valve may be employed and that it be actuated by any suitable means. In Fig. 5 of these drawings, I have shown the damper louvers *d* as being equipped with supporting hinge or pivot shafts *s*, each to be supported in a frame structure *f*, and to be equipped with a lever arm *g* at one end; all lever arms of the same damper being pivotally connected to a rod *h*, which may extend to an actuating device, such as designated at *k*.

Assuming the system to be so arranged, its mode of use is as follows:

At the start of filling the storage rooms, the boxed fruit is stacked along the side walls of the rooms, thus leaving the center space open for convenience of the workmen. As the filling of the areas continues, the stacks of boxed fruit progress toward the center of the areas; it being understood that the stacking of boxes is such as to permit the required or desired circulation of cold air through and about the boxes for the uniform cooling of all. While workmen are operating in the rooms, it is desirable that the direction of air circulation be so controlled that the cold air will enter the areas from the ducts that are near the side walls, thus to avoid the direct discharge of cold air from the central ducts 20 and 21 onto the workmen which is detrimental to their health.

In order that the cold air may be directed into the areas from the ducts that extend along the side walls, that is, from the ducts 21, 28, 29 and 30, the dampers 45 and 49 are closed and dampers 42, 46 and 50 are opened. The air, discharged by the fan 10, then enters duct 17 from the cooling unit, is directed through open damper 46 into duct 25, passing therewith through damper 50, then continuing along the duct into the laterally directed ducts 25r and 25L to the ducts 27, 28, 29 and 30, to be discharged from these into the areas to be cooled. This cooling air flows toward the central zones of the areas, and is ultimately drawn into the ducts 20 and 21, and is returned thereby into the lower end of duct 17, passing directly upward through the open damper 43 into duct 40 and is conveyed therein back to the fan, passing thereto through the openings 13 in the opposite end walls of the fan housing. This direction of circulation is opposite that which has been indicated by the arrows in the drawings.

For the reversal of the direction of air flow, the dampers 45 and 49 are opened while the dampers 42, 46 and 50 are closed, as has been shown in Fig. 10. Then the return air delivered to the fan is discharged, as before, through the cooling unit into duct 17 and is delivered through open damper 45 to the ducts 20 and 21, to be conveyed therein directly to the areas to be cooled and discharged through the duct openings 24 into these areas along the center line of the building. This air is caused to flow toward the side walls and is finally drawn into the ducts 21, 28, 29 and 30 and is returned thereby to ducts 25r and 25L, which deliver it to duct 25, from which it flows through open damper 49 to duct 40 for return to the fan.

It is to be noted that, regardless of direction of circulation, the air always passes through the fan and cooling unit in the same direction, and is thoroughly washed, cooled and humidified in each cycle of travel.

Among the many advantages to be obtained in the present system are the following:

By reason of periodic reversal of the direction of flow of cold air, a more uniform temperature may be maintained throughout the areas to be cooled, and the objectionable feature found in the one-way systems, of keeping fruit that is nearest to the inlet of cold air always at a lower degree than that fruit farthest away, is avoided.

By reason of the provision for reversal at will of direction of flow of cooling air, the field heat may be more quickly extracted from the fruit, for the reason that it is possible to employ air at lower temperatures, for example, below 30° F., and to avoid freezing the fruit nearest the air delivery points by reversing the direction when that degree in the fruit, near the freezing point, is reached.

Due to the fact that the field heat can be more quickly extracted from the fruit, the expense of this very heavy load immediately following the filling of the building, is materially reduced, and then during the entire storage period, the desired temperature may be uniformly maintained, at lower cost, by reason of the provision for periodic reversal of direction of flow.

25 The provision for causing the cold air to be discharged directly from the side wall ducts against the fruit as stacked along the outside walls, while workmen build the stacks toward the center of the areas, avoids loss of low temperature by reason of long distance of travel of cold air in reaching the fruit and also avoids the discomfort to the workmen and the unhealthful conditions of a direct discharge of cold air into the central working areas.

35 It is evident that the size of the building, the disposition of areas, and the arrangement and design of ducts is not material to the invention so long as the spirit and objects of the invention are retained. Therefore, it is not desired that 40 the claim shall be restricted or confined to details, but that they shall be given an interpretation that is commensurate to the invention that has herein been disclosed.

45 Having thus described my invention, what I claim as new therein and desire to secure by Letters Patent is—

The combination with an enclosed storage area equipped at horizontally spaced locations therein with two ducts for circulation of conditioned air through the said area selectively in either direction between the ducts, of an air conditioning and circulating unit comprising a housing having an air inlet and having an air discharge duct and means in the housing for conditioning the air in passing therethrough and for effecting a forced one-way flow of air through the unit; said air discharge duct having individual outlets connected with the two ducts of the system, valves applied to said outlets, one to be opened and the other to be closed to selectively determine the direction of flow of conditioned air through the storage area, an enclosure about the unit forming a passageway in open communication with the said air inlet of the unit housing and having individual return passages from the two ducts of the system, valves in said last mentioned openings, one to be opened and the other closed to provide for return of air to the conditioning unit through one duct while the other is used for the delivery of conditioned air to the area.

LUDWIG O. SOLBERG.
